UNITED STATES PATENT OFFICE.

JOHN F. BYRNE, OF KALAMAZOO, MICHIGAN, ASSIGNOR TO STANDARD PAPER COMPANY, OF KALAMAZOO, MICHIGAN.

DISPLAY BOX.

Application filed October 17, 1924. Serial No. 744,158.

To all whom it may concern:

Be it known that I, JOHN F. BYRNE, a citizen of the United States, residing at the city and county of Kalamazoo, State of Michigan, have invented certain new and useful Improvements in Display Boxes, of which the following is a specification.

This invention relates to improvements in display boxes.

10 The main object of this invention is to provide an improved display box in which the goods may be packed for shipping or storage and the box easily adjusted for effectively displaying its contents.

15 A further object is to provide a box having these advantages which is comparatively economical in the matter of material and is strong and durable as a box.

20 Objects pertaining to details and economies of my improvements will definitely appear from the detailed description to follow.

I accomplish the objects of my invention by the devices and means described in the 25 following specification. The invention is clearly defined and pointed out in the claims.

A structure which is a preferred embodiment of my invention is clearly illustrated in the accompanying drawing forming a 30 part of this application, in which:

Fig. I is a perspective view of my improved display box adjusted for display purposes.

Fig. II is a transverse central section of 35 the box closed.

Fig. III is a vertical transverse section on a line corresponding to line 3—3 of Fig. I.

Fig. IV is a plan view of one of the blanks used in making the box.

40 Fig. V is a plan view of the blank from which the body of the box is formed.

In the drawing similar numerals of reference indicate similar parts in all of the views.

45 Referring to the drawing, my improved box comprises a body member having a front wall 1, a rear wall 2 and end walls 3 formed as a unit. The blank from which these walls are formed is shown in Fig. V. The flap 4 at one end of the blank is lapped upon and secured to the opposite end. I provide a second unit consisting of the bottom 5, and the top 6, the bottom having a flap or

front wall section 7 which is disposed on the inner side of and secured to the front wall 1, preferably by gluing thereto.

The rear wall section 8 between the top and bottom is adapted to telescope within the rear wall 2. The bottom 5 is provided with end wall sections or flaps 9 adapted to telescope within the end walls. These flaps 9 are rearwardly tapered so that when the bottom is supported in an inclined position the upper edges do not project.

The rear wall section 8 is provided with 65 projecting ears 10 at each end adapted to swing over the end walls thereby supporting the bottom 5 in a forwardly inclined position as shown in Figs. I and III. The cover 6 is provided with a closure flap extension 11 adapted to be tucked within the front wall as shown in Fig. II. The cover or top is preferably longitudinally scored at a central point as at 12 to facilitate folding the top upon itself, the top in the structure 70 illustrated having a figure 13 cut out from the outer portion thereof so that when this outer portion is folded back, the figure stands up as shown in Fig. I.

To hold the parts in display position the 80 flap 11 is provided with a tongue 14 adapted to engage a slit 15 in the rear wall 2 of the box. The end walls are preferably provided with flaps 16 which fold below the cover, when the box is closed, thus more effectively 85 closing the ends of the box. These flaps 16 terminate short of the rear ends of the end walls so that the ears 10 may engage the same.

The box may be shipped or stored in the 90 knock-down or collapsed form. It is easily erected and conveniently adjusted to display position as desired.

Having thus described my invention what I claim as new and desire to secure by Letters Patent is:

1. A display box comprising a body member having front, rear and end walls, the end walls having closure flaps on their upper edges terminating in spaced relation to 100 the rear ends of the end walls, a bottom having a front wall section secured on the inner side of said front wall and a rear wall section adapted to telescope within said rear wall and rearwardly tapered end flaps 105 adapted to telescope within the end walls,

said rear wall section having ears at the ends thereof adapted to be engaged over the end walls at the rear of their said flaps for supporting the bottom in a forwardly inclined position, and a cover integral with said rear wall section and having a closure flap at its front edge adapted to fold within the front wall, said cover being scored longitudinally to facilitate its being folded rearwardly upon itself, its said flap having a tongue on its edge, the rear wall of the body having a slit adapted to receive said tongue for holding said cover in its adjusted position.

2. A display box comprising a body member having front, rear and end walls, a bottom having a front wall section secured on the inner side of said front wall and a rear wall section adapted to telescope within said rear wall, said rear wall section having ears at the ends thereof adapted to be engaged over the end walls for supporting the bottom in a forwardly inclined position, and a cover integral with said rear wall section, and having a closure flap at its front edge adapted to fold within the front wall, said cover being scored longitudinally to facilitate its being folded rearwardly upon itself, its said flap having a tongue on its edge, the rear wall of the body having a slit adapted to receive said tongue for holding said cover in its adjusted position.

3. A display box comprising a body member having front, rear and end walls, the end walls having closure flaps on their upper edges terminating in spaced relation to the rear ends of the end walls, a bottom having a front wall section secured on the inner side of said front wall and a rear wall section adapted to telescope within said rear wall and rearwardly tapered end flaps adapted to telescope within the end walls, the said rear wall section having ears at the ends thereof adapted to be engaged over the end walls at the rear of their said flaps for supporting the bottom in a forwardly

inclined position, and a cover integral with said rear wall section.

4. A display box comprising a body member having front, rear and end walls, a bottom having a front wall section secured on the inner side of said front wall and a rear wall section adapted to telescope within said rear wall, said rear wall section having ears at the ends thereof adapted to be engaged over the end walls for supporting the bottom in a forwardly inclined position, and a cover integral with said rear wall section.

5. A display box comprising a body member having front, rear and end walls, a bottom secured to the front wall and having a rear wall section adapted to telescope within the rear wall and end flaps adapted to telescope within the end walls, said rear wall section having ears at the ends thereof adapted to be engaged upon the end walls for supporting the bottom in a forwardly inclined position, and a cover extending from said rear wall section and having a closure flap at its front end adapted to fold within the front of the box, said cover being scored longitudinally to facilitate its being folded rearwardly upon itself, its said flap having a tongue on its edge, the rear wall of the body having a slit adapted to receive said tongue for holding said cover in its adjusted position.

6. A display box comprising a body member having front, rear and end walls, a bottom secured to the front wall and having a rear wall section adapted to telescope within the rear wall and end flaps adapted to telescope within the end walls, said rear wall section having ears at the ends thereof adapted to be engaged upon the end walls for supporting the bottom in a forwardly inclined position, and a cover extending from said rear wall section.

In witness whereof, I have hereunto set my hand.

JOHN F. BYRNE.
